Specification of Letters Patent.

Patented Dec. 9, 1919.

Application filed July 24, 1917. Serial No. 182,456.

To all whom it may concern:

Be it known that we, SAMUEL B. WILLIAMS, Jr., and RALPH L. QUASS, citizens of the United States, residing at Brooklyn, in the county of Kings and State of New York, and at Hawthorne, in the county of Passaic and State of New Jersey, respectively, have invented certain new and useful Improvements in Telephone Systems, of which the following is a full clear concise and exact description.

This invention relates to a telephone system of the call distributing type, in which calling subscribers' lines are automatically extended to idle operators' positions where the connection of the calling line with the called line is completed.

In order to secure the greatest flexibility of connection and the maximum efficiency of operation, the call distributing system of the present invention is so organized that each calling subscriber's line has access to all of the operators' positions, so that as long as there is any operator's position available, the calling line may have its connection extended. Generally stated, the invention herein set forth, contemplates the arrangement of the telephone lines in groups, and the association with each group of a group of call-extending circuits, every one of which circuits has access to all of the telephone lines of the associated group and also to all of the operators' positions of the exchange. Each operator's position is provided with a plurality of connecting circuits, and through the medium of these connecting circuits, to which the call-extending circuits are automatically extended, the operator is enabled to complete the connection of the calling line with any line of the exchange.

When a subscriber calls, a particular one of the call-extending circuits of the associated group is automatically started and brought into connection with the terminals of the calling line, the control exercised by the calling lines over the call-extending circuits being through the medium of a controlling circuit which is common to all of the telephone lines of that particular group. Likewise, when the call-extending circuit has been selected and caused to connect with the terminals of the calling line, it selects a particular one of the available operators'

positions through the medium of another controlling circuit that is common to all of the call-extending circuits of the associated group. Inasmuch as these controlling circuits are common to a number of call-extending circuits, it follows that anything which affects the operativeness of the common controlling circuits also affects the availability of all of the call-extending circuits which they serve.

It is the particular object of this invention to provide an organization whereby the large group of call-extending circuits over which each group of lines has access to any and all of the operators' positions, is divided into a plurality of sub-groups, each of which sub-groups has its own controlling circuit; and to provide switching mechanism, either automatically or otherwise operated, whereby the sub-groups of call-extending circuits are normally operated as a single large group, but may be divided into sub-groups either at will, or automatically when trouble occurs in the common controlling circuit of either sub-group, and the calls from the subscribers' lines directed over the call-extending circuits of that sub-group which is in serviceable condition, and excluded from the other sub-group. Other related or subordinate objects of the invention will appear from the description which follows.

The preferred embodiment of the invention is illustrated in the accompanying drawings, in which Figure 1 is a graphic representation of the arrangement of the apparatus and scheme of the circuits in a call distributing system organized in accordance with the invention; and Figs. 2, 3, 4, 5, 6 and 7, taken together and arranged side by side in the manner indicated by the lines extending to the margins of the drawings, illustrate as much of the circuit organization of the complete system as is necessary for an understanding of the operation of the circuits.

Referring first to Fig. 1, this is a conventionalized perspective view of a part of the lay-out of such a system, in which are indicated some of the switchboard sections, some of the line finder and cord selector frames, groups of call-extending circuits between the line finder and cord selector frames with their controlling circuits, the

- cables extending from the cord selector frames to the operators' positions on the switchboard sections, and the subscribers' line cables extending to the switchboard and 5 to the line finder frames. The line finder frames FF^1 and FF^2 are shown interconnected, by means of finder or call-extending circuits F , with corresponding cord selector frames SF^1 , SF^2 . Each of the line finder frames FF^1 , FF^2 serves as the terminal of a 10 plurality of subscribers' lines extending to the frame in the line cables LC^1 , LC^2 respectively, and each of the cord selector frames SF^1 , SF^2 serves as the terminal of 15 a plurality of connecting cord circuits, the conductors of which are carried in the cables OC^1 , OC^2 , OC^3 , OC^4 to the various operators' positions 1, 2, 3, 4, etc., on the switch board SB. The line finder frames FF^1 , 20 FF^2 and the cord selector frames SF^1 , SF^2 with their associated switches, may be of the type which is illustrated in Patent No. 1,177,044 to James L. McQuarrie, issued March 28, 1916, to which more particular 25 reference will be made hereinafter.
- In the specific embodiment of the invention diagrammatically represented in Fig. 1, each of the line finder frames FF^1 , FF^2 may 30 serve as the terminal of five hundred subscribers' lines divided into ten groups of fifty lines each. On each side or face of the line finder frame, and coöperating with the five hundred line terminals which are multiplied to appear on both sides or faces, there may 35 be thirty elevators or movable switches, each serving as the terminal of an associated finder circuit F . Each of the cord selector frames SF^1 , SF^2 may serve as the terminal of nineteen groups of connecting cord circuits, 40 each group containing the conductors of twenty-five connecting circuits extending by way of the cables OC^1 , OC^2 , etc., from a different operator's position. On each side or 45 face of each cord selector frame SF^1 , SF^2 , there may be thirty elevators or switches, each serving as a terminal of one of the 50 finder circuits F , the other terminal of which is a corresponding elevator on the corresponding line finder frame FF^1 , FF^2 . Thus 55 the five hundred telephone lines which terminate on each line finder frame FF^1 , FF^2 have access by way of sixty finder circuits, arranged in two sub-groups of thirty finder circuits each, to the cord circuits of the entire 60 group of nineteen operators' positions, which cord circuits are also multiplied to the other cord selector frames and thus made available to the call-extending or finder circuits served by those frames.
- 65 Each line cable LC^1 , LC^2 , LC^3 , etc., carrying conductors of five hundred lines, terminates upon a different one of the line finder frames FF^1 , FF^2 , etc., and also extends to multiple spring jacks accessible to 70 all of the operators at different positions of

the switchboard SB. It will be understood, of course, that only enough of the whole equipment is shown to illustrate the scheme of interconnection.

The finder or call-extending circuits F 70 that extend between each finder frame FF and its associated selector frame SF , are divided into two sub-groups G' and G^2 . The finder circuits of one of these sub-groups may terminate upon the elevators upon the 75 front of the two connected frames, and the finder circuits of the other sub-group G^2 may terminate upon the elevators on the back of the said frames. Each finder circuit is provided with a finder sequence switch FSS 80 through the medium of which the movements of the associated elevators are controlled. Each line finder frame has starting apparatus SA common to the five hundred lines thereof, and the operative relation of this 85 starting apparatus with the finder circuits of one or the other, or both, of the sub-groups G' and G^2 is determined by single group apparatus SGA . The single group apparatus SGA is represented diagrammatically 90 as two normally closed switches, each of which has an associated magnet for opening the switch. As shown, the starting apparatus of the frame is normally in operative relation with the finder sequence switches 95 FSS of both sub-groups G' and G^2 .

Associated with each sub-group of finder circuits is an operator's selecting apparatus OSA under the control of and controlling the finder sequence switches of the associated sub-groups, and also under the control of the operators' positions the connecting circuits of which terminate upon the cord selector frame SF . The operator's selecting apparatus of each sub-group controls the 100 trip magnets TM on the corresponding side of the cord selector frame, and also controls the switch governing the connection of the starting apparatus SA with the associated 105 sub-group of finder circuits.

In outline, referring to Fig. 1, the operation is as follows: When a subscriber calls whose line terminates for instance, on the line finder frame FF^1 , the act of taking the telephone receiver from its hook operates the 110 trip magnet TM corresponding with the group of fifty lines in which the calling subscriber's line is located. It also actuates the starting apparatus SA in the common controlling circuit associated with this line 115 finder frame; and the starting apparatus in operating appropriates one of the finder circuits F which has been preselected, and starts the line-finding elevator or switch of that 120 finder circuit hunting for the calling line.

If the single group apparatus SGA associated with the controlling circuit of the finder frame FF^1 is in its normal condition, the starting apparatus is in operative relation with both sub-groups G' and G^2 of finder or 125

call-extending circuits F, and the elevator of whichever one of the finder circuits F has been preselected for taking the next call, is started. That is, the finder circuits of the two sub-groups, G' and G², are working together as a single group of circuits, any one of which may extend the call of a calling subscriber's line. If the operator's selecting apparatus OSA of one of the sub-groups is not operating properly, or if it is desired for any reason to throw the circuits of that sub-group out of service, the switch of the single group apparatus SGA controlling the connection of the starting apparatus SA with that particular sub-group, is opened, thus operatively dividing the single group into two sub-groups and depriving the starting apparatus of control over the finder sequence switches of the circuits of that particular sub-group.

Assuming that the single group apparatus SGA associated with the finder frame FF¹ is in its normal position, as shown, a preselected finder circuit in one or the other of the sub-groups G' or G² is appropriated and its line finder elevator started and brought into engagement with the terminals of the calling line. When this happens, the finder sequence switch FSS of the finder circuit coöperates with the corresponding operator's selecting apparatus OSA of the cord selector frame SF¹ to select an unengaged operator's position, start the cord selector elevator of the appropriated finder circuit, trip the set of brushes corresponding with the selected operator's position, and cause the brushes to find the terminals of an idle cord circuit of that position and make connection with them. The operator at the position selected, having communicated with the calling subscriber and learned the number of the line wanted, completes connection with it by inserting the plug of the chosen connecting cord circuit at her position into the spring jack of the called subscriber's line.

Referring now to the specific embodiment of the invention as illustrated in Figs. 2 to 7 inclusive of the drawing, this embodiment is represented as comprising telephone lines extending from stations as A and A' to stationary terminals upon the opposite faces or sides of a line finder frame FF¹, the right-hand side or front of the frame being served by a plurality of line finder switches or elevators LF, LF', etc., and the left-hand side or back of the frame being served by a plurality of line finder switches or elevators LF², LF³, etc. Each line has associated with it a line relay 12 and a cutoff relay 11, and each group of fifty lines on the frame has associated with it a common protective relay 149, and also certain group apparatus designated as LG and LG'. The group apparatus is connected through the medium of

conductors 57 and 58 with the starting and single group apparatus, which apparatus is common to all of the groups and to the five hundred lines terminating upon the line finder frame, and is shown in Fig. 4. This common starting and single group apparatus is connected through the medium of the conductors 25, 26, 27, 28, 29, 78, 79 and 80 with the apparatus of the group of finder circuits F, F', F², etc., associated with the line finder switches or elevators on the front of the frame, and through the medium of the conductors 25', 25², 26', 27', 28', 29', 78', 79' and 80' with the apparatus of similar finder circuits associated with the line finder elevators or switches on the back of the frame. As the finder circuits F, F', F², etc., are alike, only one of them is shown completely. The finder circuits F, F', F², etc., terminate in cord selector switches or elevators CS, CS', etc., and through the medium of these, operating under the control of associated operator's selecting apparatus OSA, the finder circuits are adapted to have their connections extended to any one of the connecting cord circuits 85, 86, 87 and 88 at any one of the operators' positions such as are indicated at O and O'. Each one of the connecting cord circuits of the group at each of the operator's positions may be equipped as illustrated, and may terminate in a plug 170 which may be inserted in a multiple springjack 14 of a line extending to a called subscriber's station A². The multiple connection of the circuits of the various operators' positions with different cord selector frames, which is shown clearly in Fig. 1 of the drawing, is indicated in the circuit diagram by the stub connections shown at SF². These stub-connections may be understood to represent connections of the same sort as are shown fully at SF¹ in the circuit diagram.

As heretofore stated, the line finder switches LF, LF', and the cord selector switches CS, CS' may be substantially like the switch illustrated and described in Patent 1,177,044 to James L. McQuarrie, issued March 28, 1916. The line finder and cord selector switches are alike in all substantial respects. Each comprises a longitudinally movable shaft 1 carrying as many sets of brushes 2 as there are groups of stationary terminals to be engaged. To move the shaft up, an extension at the lower end of the shaft is brought into engagement with the constantly rotating power member 3 by means of an idler wheel operated by the up-drive magnet 32; and to move the shaft down, the extension is brought into engagement with the power member 4 by means of an idler wheel operated by the down-drive magnet 62. Normally the brushes of each of the sets 2 are held apart so as to clear the associated terminals by means of a separat-

ing cam 5 located between the innermost brushes of the set. The cam 5 is rotatably mounted, and when rotated in one direction releases the brushes and permits them to engage the associated terminals. The tripping or releasing of the brushes is controlled by a number of trip magnets, as 16 and 17. Each of these when energized rotates an associated trip rod 6 that extends transversely to 10 the switch shafts 1 and carries as many trip yokes 7 as there are finder switches in the group. The trip rod in rotating brings all of its trip yokes 7 into position to operate the brush-controlling cams 5 of the corresponding sets of brushes on all of the switches, so that whichever of the finder switches is caused to move up has that set of brushes tripped that corresponds with the particular trip magnet 16, 17, that is at 15 the time energized. When the finder switch that has been in use is returned to its normal position, any of the associated controlling cams 5 that has been tripped is engaged and rotated in a reverse direction to separate its switch springs again and thus render them inactive. Each of the line finder and cord selector switches has associated with it a commutator 8 which comprises a number of stationary commutator segments and a set of 20 movable brushes carried at the top of the switch shaft 1 and coöperating with the stationary segments. This commutator serves to make and break a number of the controlling circuits in the various stages of the upward movement of the switch shaft.

For controlling the circuits of the organization there are employed a number of sequence switches which are shown at different points and are designated 100, 200, 300, 500 and 600, respectively. These sequence switches may be of the type disclosed in Patent 1,127,808, issued February 9, 1915, to Reynolds and Baldwin. Each consists of an electro-magnetically controlled 40 motor or driving mechanism and a number of associated switch cams. The switch cams associated with each of the sequence switches 100 are designated 101 to 103, inclusive; those associated with each of the sequence switches 200 are designated with numerals between 201 and 228, inclusive; those associated with each of the sequence switches 300 are designated 301 to 304 inclusive; those associated with the sequence switch 500 are designated 501 to 515 inclusive and those associated with the sequence switch 600 are designated 601 to 617 inclusive. To each of the contacts associated with the various sequence switch cams are applied certain numerals. These numerals in the case of the cams 101, 201, 301, 501 and 601 indicate the only positions of the associated sequence switch in which these particular contacts are open; the numerals applied to all of the other contacts

of each sequence switch indicate the only positions of the particular sequence switch in which the associated contacts are closed.

The sequence switches 100 merely act as timing switches and have only one resting 70 position. The resting positions of the other sequence switches, and the stages of operation with which these positions are associated, are as follows:

Sequence switch 200.

1. Normal.
2. Awaiting starting circuit.
3. Awaiting starting circuit release.
4. Hunting calling line.
5. Awaiting preceding finder circuit.
6. Awaiting operator's selecting circuit.
7. Awaiting operator's selecting circuit.
8. Releasing operator's selecting circuit.
9. Hunting cord circuit.
14. Talking.
15. Line finder at telltale.
16. Line finder return.
17. Cord selector return.

Sequence switch 300.

1. Awaiting a call.
4. Position vacant.
17. Position busy.

Sequence switch 500.

1. Finders in one group.
3. Front of frame shut down.
8. Awaiting finders on regrouping.

Sequence switch 600.

1. Finders in one group.
3. Back of frame shut down.
8. Awaiting finders on regrouping.

The operation of the system as illustrated in the accompanying drawings is as follows: 105 When a subscriber calls, the taking of the telephone receiver from its hook closes a circuit in the usual way that causes the energization of the associated line relay 12 at the central office. The line relay in operating closes a circuit that extends from battery through the winding of relay 19 of the group in which the calling line is located, contacts 103 (18 $\frac{3}{4}$ to 1 $\frac{1}{4}$) of sequence switch 100 of that group, group conductor 18, and armature and front contact of line relay 12 to ground. Relay 19 in operating closes a circuit that extends from battery through the right-hand winding of relay 24, front contact and armature of relay 19, conductor 57, inner back contact and armature of relay 22, and left-hand back contact and armature of relay 23, to ground. Relay 24 in operating closes a locking circuit for itself in its left-hand contact and armature and in doing so 110 causes the operation of the associated tripping magnets 16 on the front and back of the frame, the energizing path for the tripping magnets and for the left-hand or locking winding of the relay 24 being, by way 115

of the left-hand front contact and armature of relay 24, conductor 58, winding of relay 22, and right-hand armature and back contact of relay 23, to ground. Relay 24 in operating also closes a circuit that extends from battery through the motor magnet of the associated sequence switch 100, sequence switch contact 102 (18 $\frac{3}{4}$ to 11) and right-hand contact and armature of relay 24 to ground. The closure of this circuit moves sequence switch 100 out of position 1, whereupon the switch continues to rotate, under the control of its governing cam 101, until it completes its cycle and again comes to rest in position 1, the circuit by way of cam 102 (18 $\frac{3}{4}$ to 11) opening in the meantime as a result of the release of the relay 24. While the sequence switch 100 is rotating it maintains open in sequence switch contact 103 (18 $\frac{3}{4}$ to 11) the connection of the relay 19 with the group conductor 18, so that during this period the relay 19 is not under the control of the line relays 12. During this interval the calling line is found and the line relay 12 deenergized to remove the ground from conductor 18, as will hereinafter be described.

Included in the circuit by way of conductor 58 closed upon the initiation of a call, as described above, is the winding of the starting relay 22. This relay in operating closes the circuit of the starting conductor 129, and in doing so brings about the movement of a line finder switch in one or the other of the two divisions or sub-groups of switches LF, LF', LF² and LF³ that have access to the terminals of the five hundred lines in which the line assumed to be calling is located. The two divisions or sub-groups are preferably those on the back and front of the line finder frame, as already indicated; but if desired the switches may be divided into sub-groups in any other convenient manner.

Associated with the relay 22 in the control of the finder switch starting operation, are the relays 23 and 33, and the control of the starting operation is exercised through the medium of the conductors 125, 126, 127, 128 and 129. The operative relation between these conductors and the circuits and apparatus of the finder switches is under the control of the two grouping sequence switches 500 and 600 forming a part of the single group apparatus. Each of these sequence switches when it is operated serves to direct the calls into the sub-group of finder switches with which it is associated, and exclude calls from the other sub-group. Thus when the sequence switch 500 is energized to move its cams into position 3, the calls originated in the five hundred lines of the associated frame are taken by the finder switches on the back of the frame and excluded from the finder switches on the front of the frame; when the sequence switch 600

is energized to move its cams into position 3, the starting apparatus is operatively associated with the finder switches on the front of the frame to cause these switches to take the calls, while the switches on the back of the frame are cut off. When both of the sequence switches 500 and 600 are standing in position 1, the starting apparatus, including the relays 22, 23 and 33, is operatively associated with the finder switches on both the front and back of the frame, these switches at such time acting as a single group in taking the calls originated by the associated 500 lines.

The manner in which the two grouping sequence switches 500 and 600 are operated, will be explained later. For the present, only the result of that operation upon the circuits extending from the starting apparatus will be described. When both se- 80

quence switches 500 and 600 are standing in position 1, the starting conductor 129 is connected by way of grouping sequence switch contact 612 (1) with all of the sequence switch contacts 206 (2) associated 90 with the sub-group G² of finder circuits F, F' and F² extending to finder switches on the back of the frame and is connected by way of grouping sequence switch contact 512 (1) with all of the sequence switch contacts 206 (2) associated with the sub-group G' of finder circuits extending to finder switches on the front of the frame. In like manner, the conductor 127 of the starting apparatus is connected by way of sequence switch contact 510 (1) with the sequence contacts 203 (3) of all of the finder circuits on the front of the frame, and is connected by way of sequence switch contact 610 (1) with the sequence switch contacts 203 (3) of all of the finder circuits on the back of the frame. Conductor 126 of the starting apparatus is connected by way of sequence switch contact 514 (1) with the sequence switch contacts 209 (2 $\frac{3}{4}$ to 3) of all of the finder circuits on the front of the frame, and is connected by way of sequence switch contacts 614 (1) with the sequence switch contacts 209 (2 $\frac{3}{4}$ to 3) of all of the finder circuits on the back of the frame. Conductor 110

128 of the starting apparatus is connected by way of sequence switch contact 507 (1) with the sequence switch contacts 211 (3 to 3 $\frac{1}{2}$) of all of the finder circuits on the front of the frame, and is connected by way of sequence switch contact 607 (1) with the sequence switch contacts 211 (3 to 3 $\frac{1}{2}$) of all of the finder circuits on the back of the frame. Conductor 115 120 of the starting apparatus, when both sequence switches 500 and 600 are in their normal or 1 position, is connected by way of sequence switch contact 616 (1), sequence switch contact 515 (1), and sequence switch contact 615 (1) serially through the sequence switch contacts 210 130

(2₄ to 1) of all of the finder circuits on both sides of the frame and to ground at the end of the series.

When sequence switch 600 is operated to move its cams to position 3, sequence switch 500 remaining in position 1, the starting apparatus conductors 126, 127, 128 and 129 are left connected by way of the cams of sequence switch 500 with the cams 209, 203, 211 and 206, respectively, of the sequence switches associated with the finder circuits on the front of the frame, and are cut off, at the cams of sequence switch 600, from the sequence switch cams 209, 203, 211 and 206 associated with the finder circuits on the back of the frame. In like manner the movement of sequence switch 500 into position 3, sequence switch 600 remaining in position 1, leaves the starting apparatus conductors 126, 127, 128 and 129 connected by way of the contacts of sequence switch 600 with the switch cams 209, 203, 211 and 206 associated with the finder circuits on the back of the frame, and disconnects them at contacts of sequence switch 500 from the corresponding sequence switch cams of the finder circuits on the front of the frame.

The cutting out of the finder sequence switch cam series 210 of the finder circuits on the back of the frame is accomplished when sequence switch 600 moves into position 3, by the disconnecting at contact 615 (1) and 616 (1) of the part of the loop circuit extending through these cams, while at the same time the conductor 125 is connected at sequence switch contacts 615 (3) directly to the series of sequence switch cams 210 associated with the finder circuits on the front of the frame. The cutting out of the 210 cam series of the finder circuits on the front of the frame is accomplished when sequence switch 500 is moved to position 3, by disconnecting from conductor 125 at sequence switch contact 515 (1) the part of the loop including the series associated with the front of the frame, while at the same time a ground for the 210 cam series of the back of the frame is applied at sequence switch contacts 515 (3).

Thus, while the conductors of the starting apparatus are operatively associated with the finder circuits of both the front and back of the frame when the sequence switches 500 and 600 are standing in position 1, the movement of either of these sequence switches to position 3 associates these starting apparatus conductors exclusively with the finder circuits of the side of the frame corresponding with the sequence switch that is operated.

Continuing with the description of the operation of the system, it will be assumed that both of the sequence switches 500 and 600 are in their normal or 1 position. For reasons that will hereinafter be explained,

only one of the sequence switches 200 of the entire group of finder circuits can be resting in position 2 under the conditions assumed. Assuming that this is the sequence switch of finder circuit F in sub-group G' on the front of the frame, when the relay 22 is actuated by the calling line, as already described, a circuit is completed that extends from battery through the left-hand winding of relay 30, conductor 67, sequence switch contacts 206 (2), conductor 29, sequence switch contact 512 (1), conductor 129, inner front contact and armature of starting relay 22, right-hand armature and back contact of relay 23 to ground. The right-hand winding of relay 30 is at this time also included in parallel with the left-hand winding of the relay in the energizing circuit, the parallel branch being from battery through resistance coil 56, sequence switch contacts 217 (2 to 9), right-hand winding of relay 30, conductor 241, sequence switch contacts 220 (2) and (1 to 13), thereafter joining the conductor that extends from the left-hand winding of relay 30, and to ground over the circuit already traced. The effect of this is to give the relay 30 the benefit of the energizing action of both windings. Relay 30 in operating closes a locking circuit for itself that extends from battery through resistance coil 56, sequence switch contacts 217, (2 to 9), right-hand winding of relay 30, sequence switch contacts 216 (2 to 9), left-hand front contact and armature of relay 30, and armature and back contact of relay 52 to ground. Relay 30 also closes a circuit that extends from battery through the motor magnet and cam 202 (2) of sequence switch 200, right-hand front contact and armature of relay 30, sequence switch contacts 208 (2 to 7), conductor 70, and segment M of the cord selector commutator and corresponding brush to ground. The closure of this circuit causes sequence switch 200 to move out of position 2 and come to rest in position 3.

In position 3 of the switch, a circuit is closed that extends from battery by way of the up-drive magnet 32 of the corresponding line finder switch LF, conductor 59, sequence switch contact 207 (3 to 4), front contact and right-hand armature of relay 30, sequence switch contact 208 (2 to 7), and to ground by way of segment M of the cord selector commutator. The energization of the up-drive magnet 32 starts the upward movement of the corresponding elevator rod with its associated sets of brushes. At the outset of the upward movement of the elevator rod, all of the brush-trip levers are moved past the corresponding trip yokes. The only trip magnet that is energized in this case is the magnet 16 which corresponds with the group in which the calling line is

assumed to be located; and consequently the only trip yoke in position to engage a trip lever on the elevator rod is the one which controls the brushes 40, 41, 42 and 43 5 that are adapted to engage the terminals of that particular group of lines. This set of brushes, therefore, is released and made operative, and the other sets are held clear of their associated line terminals.

10 As soon as the set of brushes corresponding with the calling line is tripped, the apparatus by means of which the lines control the brush-tripping and finder-starting operations, may be returned to its normal condition. The first step in this restoring operation is effected by the closure of a circuit which is completed by way of the K segment of the line finder commutator immediately after the brushes are tripped. 15 This circuit extends from battery in parallel branches through the relays 23 and 33 (see Fig. 4), conductor 126, contact 514 (1) of grouping sequence switch 500, conductor 26, finder sequence switch contacts 209 (2 $\frac{1}{4}$ to 3) 20 of finder circuit F, conductor 68, and to ground by way of K segment of the line finder commutator and its associated brush. The energization of the relay 23 interrupts, in the right-hand back contact of that relay, 25 the previously described circuit that has up to this time maintained the energization of the trip magnets 16, the group relay 24 and the common starting relay 22. Relay 23, in its left-hand front contact closes a 30 locking circuit for itself and the associated relay 33 that extends by way of conductor 125, contact 616 (1) of grouping sequence switch 600, in series through the sequence switch contacts 210 (2 $\frac{1}{4}$ to 1) of all of the 35 finder circuits of sub-group G' associated with the back of the frame, grouping sequence switch contact 515 (1), grouping sequence switch contact 615 (1), and in series through contacts 210 (2 $\frac{1}{4}$ to 1) of all 40 of the finder circuits of sub-group G' associated with the front of the frame to ground at the end of the series. 45

As has already been stated, normally there is only one of the finder circuits of all 50 which serve this frame that has its sequence switch in position 2 awaiting the receipt of a call. When the call comes in, this sequence switch is immediately moved to position 3 by the energization of relay 30 in the manner 55 already described. Therefore, at this stage of the operation the sequence switches of all of the finder circuits, being either in position 1 or in position 3 and beyond, are in position to close their contacts 210. 60 The locking circuit for the relays 23 and 33 is therefore held closed by way of the 210 cam series until another one of the finder circuits has its sequence switch moved into position 2 to break the locking circuit in 65 the associated cam 210. This is accom-

plished by relay 33, which in operating applies a ground to conductor 128 to move the sequence switch of another finder circuit out of position 1 and into position 2, and which also applies a ground to the conductor 70 127 to move the sequence switch of the appropriated finder circuit out of position 3.

Assuming that the sequence switch of the finder circuit F' in sub-group G' associated with the back of the frame is in position 1, 75 and that the sequence switch of finder circuits F and F' of sub-group G' are in same position between 4 and 17, these finder circuits being assumed to be in use, the operation of the relay 33 completes a circuit from 80 battery through the motor magnet and contact 203 (1) of the sequence switch of finder circuit F' of sub-group G', contacts 211 (1) of the same sequence switch, contacts 211 (3 to 17) and (4 to 17) of sequence switch 200 85 of finder circuit F' of sub-group G', contacts 211 (3 to 17) and (4 to 17) of sequence switch 200 of finder circuit F in sub-group G', grouping sequence switch contact 506 (1), grouping sequence switch contact 606 90 (1), contacts 211 (3 to 17) and (3 to 3 $\frac{1}{4}$) of sequence switch 200 of the finder circuit F of sub-group G' (the finder circuit that has just been appropriated), grouping sequence switch contact 507 (1), conductor 128, and 95 left-hand front contact and armature of relay 33 to ground. This causes the sequence switch of finder circuit F' of sub-group G' to move into position 2. At the same time the sequence switch of finder circuit F is 100 moved out of position 3 by the closure of a circuit that extends from battery through the motor magnet and contacts 203 (3) of the sequence switch of that circuit, conductor 27, grouping sequence switch contact 510 105 (1), conductor 127, and right-hand front contact and armature of relay 33 to ground. As soon as the sequence switch of finder circuit F' of sub-group G' moves into position 2, it opens in its contacts 210, the previously 110 described circuit by way of conductor 125, which up to this moment has maintained relays 23 and 33 energized, and these relays thereupon release their armatures. Relay 23 in releasing reconnects to ground the circuit which extends in branches 57 and 58 through the various sets of line group relays LG, LG', thus again giving the line groups access to the starting circuit.

At this stage of the operation of the system, the sequence switch of the appropriated finder circuit F of sub-group G' is in position 4, and the elevator rod of the associated line-finder LF is moving up, with the set of brushes tripped that corresponds with the group in which the calling line is located. As the tripped brushes rise, they come into engagement successively with the sets of contacts corresponding with the different lines of the group. At the instant of en- 120 125 130

gagement of the brush 43 with the terminal 47 of each line, the test relay 52 of the finder circuit is connected with local conductor 65 of that line. This local conductor has two branches, one or the other of which is closed depending upon the condition of the line relay 12 of the associated line. If the line relay is inert, as it is when the line is not calling, or when the line has been connected with and its cut-off relay operated, the local conductor 65 of the line is connected with ground by way of an identifying device 150 and a relatively low potential battery. If the line relay 12 is energized, as it is when the line is calling and is not connected with, the local conductor 65 of the line is connected with ground by way of the right-hand back contact and armature of the protective relay 149 common to a group of lines, the energizing winding of this relay, and a relatively high potential battery.

Therefore, as the elevator rises and the brush 43 engages the corresponding terminal 47 of each of the lines of the group in which the calling line is located, a circuit is completed as each line terminal is engaged that extends either by way of the low potential battery, the device 150, and the left-hand back contact and armature of relay 12, or by way of the high potential battery, the winding of common relay 149, the right-hand armature and back contact of that relay, and the right-hand front contact and armature of relay 12 to the local conductor 65 of the line; and thence by way of the line terminal 47, brush 43, conductor 51, finder sequence switch contacts 215 (1 to 8) and (2 $\frac{3}{4}$ to 4), and winding of relay 52 to ground.

The relay 52 is so adjusted that it will respond only to the current flow produced in the circuit by the high potential battery, and not to that produced by the low potential battery. As the line relay 12 of the calling line is energized, thus connecting the high potential battery to the associated local conductor 65, the test relay 52 responds when the brush 43 engages the terminal 47 of the calling line. The response of the relay 52 causes that relay to interrupt in its back contact the previously-traced circuit by way of the left-hand armature and front contact of the relay 30, sequence switch contacts 216, and right-hand winding of relay 30, which circuit had been holding the relay 30 locked up from the moment that the relay was first energized upon the receipt of the call. Relay 30 in releasing its armatures breaks its own locking circuit, and also breaks the previously-traced path, including sequence switch contacts 208, right-hand armature and front contact of the relay 30, and sequence switch contact 207, over which current has been flowing to energize the up-drive magnet 32 of the line finder. Therefore, the operation of the relay 52 upon the

finding of the calling line acts to effect the instant deenergization of the up-drive magnet 32, and thus to stop the brushes upon the terminals of the calling line.

When the relay 30 is deenergized, as a result of finding the calling line, it also completes a circuit that extends from battery through the motor magnet and contact 202 (3 to 4) of the finder sequence switch, right-hand back contact and armature of the relay 30, sequence switch contact 208 (2 to 7), conductor 70, and M segment and corresponding brush of the cord selector CS to ground. The closure of this circuit moves the sequence switch out of position 4.

When finder sequence switch reaches position 4 $\frac{3}{4}$, it closes a path for the flow of current through the cut-off relay 11 of the calling line, by way of resistance coil 64, sequence switch contact 212 (4 $\frac{3}{4}$ to 12 $\frac{1}{2}$), conductor 50, brush 42, line terminal 46 and conductor 53. The flow of current in this circuit operates the cut-off relay 11 to disconnect the relay 12 from the circuit, and that relay in releasing its armature disconnects the high potential battery from the local conductor 65 and disconnects ground from the common conductor 18. The disconnection of ground from conductor 18 occurs before the timing sequence switch 100 has completed its cycle of rotation and reconnected conductor 18 with relay 19.

The brushes of the line finder switch are now at rest in engagement with the terminals of the calling line; the group starting circuit represented by the conductors 57 and 58 and the associated relays 22, 23 and 33 has been released and is in readiness to respond to another calling line, and the sequence switch of another finder circuit has been moved into position 2, and thus brought into operative relation with the starting conductor 129.

The starting of a finder switch and the seizing of a calling line having been described, it may be well at this point to consider the manner in which the shutting down of one side of the frame and the directing of the calls exclusively through the circuits associated with the other side of the frame, is effected.

The shutting down of the front of the frame is effected either by closing the circuit of the conductor 80, in a manner that will hereinafter be described, or by operating the switch or key 143. The shutting down of the back of the frame is effected either by closing the circuit of the conductor 80', in a manner that will hereinafter be described, or by operating the switch or key 144. It will be assumed in the present instance that it is desired to shut down the back of the frame in order, for instance, that repairs may be made upon certain of the switches associated with that side of the

frame. The key 144 therefore is operated, and as a result a circuit is completed that extends from battery through the winding of the relay 136 and to ground by way of 5 contacts of the key 144. The relay 136 in operating closes a circuit that extends from battery through the winding of the relay 134, single group sequence switch contact 604 (1) single group sequence switch contact 10 513 (1), right-hand front contact and armature of relay 136, conductor 140, and outer back contact and armature of starting relay 22 to ground. If at the time in question the starting apparatus is engaged in 15 starting a finder switch, the starting relay 22 will be actuated, and the circuit traced above therefore will be open at the contacts of relay 22; but if the starting apparatus is not acting, the completion of the circuit 20 traced above causes the operation of relay 134. When relay 134 operates, it closes a locking circuit for itself that extends from the winding of relay 134 to ground by way of sequence switch contact 604 (1) and the 25 right-hand armature and front contact of relay 134. Relay 134 in operating also closes a circuit that extends from battery through the windings of the relays 23 and 33 of the starting apparatus in parallel, 30 conductor 126, and front contact and right-hand armature of relay 134 to ground. Relay 23 in operating opens, at its left-hand armature and back contact, the path to ground of the conductors 57 and 58 over 35 which the control of the starting relay 22 by the calling lines is exercised, so that as long as the relay 134 is energized the starting apparatus is unresponsive to a calling line. The other connections controlled in 40 the attraction of the armatures of the relays 23 and 33 do not effect any operative change at this time. Furthermore, relay 134 in operating closes a circuit that extends from battery through the winding and contact 45 602 (1) of single group sequence switch 600, and to ground by way of the left-hand front contact and armature of relay 134. Sequence switch 600 thereupon moves its cams to position 3, and in this movement the energizing path for the relay 134 is broken at 50 sequence switch contact 604, and relay 134 becomes inert. The movement of single group sequence switch 600 to position 3 disconnects the starting apparatus from the 55 finder circuits F, F' and F² of sub-group G² associated with the back of the frame, and leaves the starting apparatus associated exclusively with the finder circuits of sub-group G' on the front of the frame, as has 60 hereinbefore been described.

At the time this change is effected, it may happen that the finder circuit next in order to be appropriated by a calling line, as determined by the standing of its sequence switch 200 in position 2, is in the sub-group

G² that the throwing of key 144 has made inoperative. It therefore becomes necessary to move into position 2 the sequence switch 200 of one of the finder circuits in sub-group G' associated with the front of the 70 frame. This is effected through the medium of the 222 cam series of the finder circuits of sub-group G', and the associated relay 138. Under the conditions assumed, all of the sequence switches 200 of the finder circuits of sub-group G' are either in position 1 or are in position 5 and beyond. A circuit therefore is completed that extends from battery through the winding of relay 138, single group sequence switch contact 75 505 (1), conductor 79, and the contacts 222 (5 to 1) of all of the finder sequence switches of the sub-group G' to ground at the end of the series. The relay 138 in operating applies a ground by way of single 80 group sequence switch contact 606 (3) to the loop that includes the sequence switch cams 211 of all of the finder circuits of sub-group G', to move into position 2 one of the sequence switches of this series that 85 is at the time standing in position 1. If it be assumed that finder circuit F² of sub-group G' is in use, with its sequence switch therefore standing in some position between 90 4 and 17, and that the sequence switch or 95 finder circuit F' is standing in position 1, when relay 138 operates a circuit is completed that extends from battery through the motor magnet and contact 203 (1) of the sequence switch of finder circuit F' of 100 sub-group G', contacts 211 (1) of the same sequence switch, contacts 211 (3 to 17) and (4 to 17) of sequence switch 200 of finder circuit F², conductor 78, sequence switch contact 606 (3), and front contact and armature of relay 138 to ground. Therefore, as soon as grouping sequence switch 600 moves into position 3, the sequence switch of a 105 finder circuit of the associated sub-group G' is moved into position 2, where it stands 110 in readiness to respond to the closure of the starting conductor 129.

It may here be pointed out that when both single group sequence switches 500 and 600 are standing in position 1 the sequence 115 switch cams 211 of each sub-group G' and G² are united with each other in a single series, the associated finder circuits thus operating as a single group. Contact 211 (3 to 17) of one sequence switch is joined to 120 the contact 211 (4 to 17) of the next sequence switch of the series; the contact 211 (3 to 17) of that sequence switch is joined to the contact 211 (4 to 17) of the next sequence switch of the series; and so on to 125 the last 211 sequence switch cam of the group, at which point the contact 211 (3 to 17) of one sub-group is connected by way of cams of the single group sequence switches to the contact 211 (4 to 17) of the 130

first sequence switch of the other sub-group. When the single group sequence switches 500 and 600 are standing in position 1, and the two sub-groups are thus working as a single group, the closing of the 222 cam series of both sub-groups at the same time acts to apply a ground to the above described circuit including the 211 cams of all of the sequence switches of both of the sub-groups, the effect of this ground being to move the sequence switch 200 of some one of the finder circuits in the two sub-groups G' and G² that happens to be standing in position 1, out of that position and into position 2. Thus when all of the sequence switch cams 222 of the finder circuits of sub-group G' are in some position from 5 to 1 inclusive, a circuit is completed for the energization of relay 138, as already described. At the same time if the cams 222 of all of the sequence switches 200 of sub-group G² are standing in some position from 5 to 1 inclusive, a circuit is closed that extends from battery through the winding of relay 137, single group sequence switch contact 605 (1), and the 222 cam series of sub-group G² to ground at the end of the series. The completion of both of the above traced circuits effects the energization of the associated relays 138 and 137, and these relays in operating apply a ground to the circuit including the 211 cams of both sub-groups, this path extending from ground by way of the armature and front contact of relay 138, right-hand armature and front contact of relay 137, grouping sequence switch contact 608 (1), and grouping sequence switch contact 508 (1). The ground path thus applied is connected over the 211 cam series by way of single group sequence contact 509 (1), single group sequence switch contact 609 (1), conductor 78, and thence through the 211 (4 to 17) and (3 to 17) contacts of one after the other of the busy sequence switches of the series until a sequence switch standing in position 1 is encountered, where the ground becomes effective by way of contacts 211 (1) and 203 (1) of that sequence switch to energize the motor magnet of the switch. If none of the sequence switches of sub-group G' is standing in position 1, then the ground is communicated to the sequence switches of sub-group G² by way of contact 211 (4 to 17) and (3 to 17) of finder circuit F of sub-group G', single group sequence switch contact 606 (1), and single group sequence switch contact 506 (1). When the single group sequence switch 600 moves to position 3, the 211 cam series of the associated sub-group G' is connected at sequence switch contact 617 (3) in a closed loop, with a controlling path to ground at the contacts of relay 138 by way of sequence switch contacts 606 (3); and at the same time the 211 cam series of sub-groups G²

is connected in a closed and independent loop by way of single group sequence switch contacts 609 (3), with a controlling path from this loop by way of sequence switch contact 605 (3) and the 222 cam series of the sub-group G². In an exactly similar manner, the movement of single group sequence switch 500 to position 3 connects the 211 cam series of sub-group G² in a closed loop at sequence switch contact 508 (3), and the 211 cam series of sub-group G' into a closed loop at sequence switch contact 509 (3), the first mentioned loop having a controlling path to ground at the left-hand front contact and armature of relay 137 by way of sequence switch contact 506 (3), and the other loop having a controlling path to ground by way of the 222 cam series of sub-group G' and sequence switch contact 505 (3). Thus the effect of moving either of the single group sequence switches into position 3 is to divide into two independent loops the series preselecting circuit of the finder circuits of the frame, and provide each of these loop circuits with its own controlling path governed by the series of finder circuits of the corresponding sub-group.

Under the assumption that the shutting down of the back of the frame and the directing of the calls through the circuits associated with the front of the frame was effected by the throwing of the switch or key 144, the back of the frame may again be restored to service, and the sub-groups G' and G² again operated as a single group, by returning the key 144 to its normal position. When key 144 is thrown back so as to open its left contact and close its right contact, the energizing circuit of the relay 136 is broken and the relay releases its armature. This closes a circuit that extends from battery through the winding of relay 134, sequence switch contact 604 (3 to 8³), back contact and armature of relay 136, conductor 140, and outer back contact and armature of starting relay 22 to ground, the control of this circuit in the resting contacts of relay 22 being in order that the regrouping operation may not take place while the starting apparatus is acting. Assuming that the starting relay is inert, the closure of the above traced circuit operates the relay 134. This relay in operating closes a locking circuit for itself by way of grouping sequence switch contact 604 (3 to 4), and right-hand front contact and armature of relay 134 to ground. Relay 134 in operating also closes a circuit that extends from battery through the motor magnet and contact 602 (3) of grouping sequence switch 600, and to ground by way of the left-hand front contact and armature of relay 134. The grouping sequence switch thereupon moves out of position 3 and comes to rest in position 8.

The grouping sequence switch 600 is held in position 8 subject to the control of the finder circuits of sub-group G^2 , which circuits will be brought into operative relation with the starting circuit by the movement of sequence switch 600 from position 8 to position 1. It may have been when the large group was divided into two sub-groups and sub-group G^2 rendered inoperative by the movement of sequence switch 600 out of position 1, that the finder circuit preselected to take the next call and with its sequence switch standing in position 2, was one of the finder circuits of sub-group G^2 .
 10 If the reuniting of the two sub-groups into one large group by the movement of sequence switch 600 from position 3 to position 1, occurs while the sequence switch of one of the finder circuits of sub-group G^2 is in the preselected or 2 position, then, inasmuch as the sequence switch of one of the finder circuits of sub-group G' is also in position 2, the first call after the two sub-groups have been thrown together again, would result in the starting of two finder switches. Therefore sequence switch 600 is held in position 8 until any sequence switch of sub-group G^2 that may be standing in position 2, is moved out of this position. This result is accomplished in the following manner: When grouping sequence switch 600 reaches position 4 in its movement to position 8, a circuit is closed that extends from battery through the windings of a pair of trip magnets—say, the magnets 17, on the associated line finder frame, conductor 130, grouping sequence switch contacts 611 (4 to 8), and resting contacts of key 144 to ground. At the same time a circuit is closed that extends from battery by way of the left-hand winding of relay 30 of the finder circuit of sub-group G^2 whose sequence switch is standing in position 2, conductor 67, finder sequence switch contacts 206 (2), grouping sequence switch contact 611 (4 to 8), and to ground by way of the resting contacts of key 144.

The result of the closure of these circuits is that sequence switch 200 of the corresponding finder circuit of sub-group G^2 is moved into position 3, the corresponding line finder elevator started up, and the set of brushes tripped that is associated with the group controlled by the trip magnets 17, all in the manner that has hereinbefore been described. As the starting of the line finder elevator is not the result of a call initiated by one of the lines of the group, no circuit is closed for the energization of the test relay 52 as the brush 43 successively engages the terminals 47 of the lines of the group, but above the last set of line terminals is placed a set of terminals 193, the test terminal of which is connected with a relatively high potential battery by way of the right-

hand back contact and armature and the winding of a protective relay 145. When therefore the set of brushes rises to the point where the test circuit is thus completed, the test relay 52 is energized, stops the brushes in engagement with the set of terminals 193, and moves the associated sequence switch 200 to position 6 in the manner that has already been described. The sequence switch is moved from position 6 to position 7 when relay 30 is energized by the completion of a circuit controlled by the operator's selecting apparatus and by the 219 cam series of the finder circuit sequence switches, in a manner that will hereinafter be described.

When the sequence switch reaches position 7, a circuit is closed that extends from battery through the motor magnet and contact 224 (7 to 15) of the finder sequence switch, conductor 120, and to ground by way of segment Z and the corresponding brush of the line finder commutator, this segment being grounded by its brush when the elevator has risen to the point where the line brushes engage the set of terminals 193. The closure of this circuit moves the finder sequence switch 200 through position 15 and allows it to come to rest in position 16. In position 16 a circuit is closed, as will hereinafter be described, that returns the line finder elevator to its normal position, after which another circuit is closed that moves the finder sequence switch 200 to position 1. Thus the movement of the grouping sequence switch 600 out of position 3, in the process of returning that switch to its normal position 1, returns to its normal position the apparatus of any finder circuit of sub-group G^2 which may have been preselected to take the next call at the time when the sub-group G^2 was disconnected from the starting apparatus.
 135

lay thereupon releases its armatures, and at its left-hand armature and inner front contact opens the connection of conductor 126 with ground. This ground connection operated while sequence switch 600 was moving from position 3 to position 8, and while it was standing in position 8, to energize relay 23 of the starting apparatus and thus deprive the lines of the associated finder frame 10 of control over the starting apparatus.

The foregoing description has been directed toward the coöperation of the key 144, the relays 134 and 136, and the grouping sequence switch 600 in shutting down the back 15 of the frame and directing the calls exclusively into the sub-group G' of finder circuits associated with the front of the frame. The key 143, the relays 133 and 135, and the grouping sequence switch 500 co- 20 operate in an exactly similar manner in effecting the shutting down of the front of the frame and the directing of the calls exclusively into the sub-group G^2 of finder circuits associated with the back of the frame. If it should happen that one side 25 of the frame is shut down when conditions arise that would ordinarily lead to the shutting down of the other side of the frame, in the manner described, the arising of this condition, instead of bringing about the movement 30 to position 3 of the grouping sequence switch that is standing in position 1, brings about the operation of the relay 23 of the starting apparatus to block all calls by opening the path to ground from conductors 57 and 58. Thus, for instance, if the grouping sequence switch 600 has been moved into 35 position 3 to shut down the back of the frame, and a condition arises that causes the energization of relay 135 and would ordinarily lead to the movement of sequence switch 500 to shut down the front of the frame, the ground that this relay applies at 40 its armature and front contact is effective by way of grouping sequence switch contact 613 (3) and conductor 126 to bring about 45 the energization of relay 23; and that relay in operating opens at its right-hand armature and back contact the path to ground of the conductors 57 and 58, thus keeping all 50 calls blocked as long as this condition continues.

In the foregoing, the keys or switches 144 and 143 were described as the means for 55 causing the operation of the grouping sequence switches to bring about a dividing of the large group into sub-groups, and the operative connection of one or the other of these sub-groups with the starting circuit. 60 In the system of this invention, the grouping operations are also under the automatic control of operators' selecting circuits and apparatus associated with the finder circuits of the two sub-groups G' and G^2 , this con-

trol being exercised by way of the conductors 80 and 80' respectively. In order to make clear the nature of this control, the operation of the system involving the selection of an operator's position and of an idle connecting circuit on that position will now 70 be described.

When the sequence switch of the finder circuit over which the call is being extended has reached position 6, as hereinbefore described, the finder circuit is brought into 75 operative relation with the operators' selecting circuit. When the finder sequence switch reaches position 6, it awaits the closing of a circuit the completion of which is dependent upon the condition of the other 80 finder circuits of the associated sub-group. This circuit extends from battery through the left-hand winding of the relay 30, conductor 243, contact 219 (6) of the appropriated circuit sequence switch, contacts 219 85 (9 to 4) of the sequence switches of the associated finder circuits of sub-group G' preceding it in the series, conductor 76, outer armature and back contact of relay 54, and right-hand back contact and armature of 90 relay 61 to ground. A branch path for the energization of the relay 30 also exists at this time, this branch path extending from battery through resistance 56, sequence switch contacts 217 (2 to 9), right-hand winding of relay 30, conductor 241, sequence switch contacts 220 (6) and (1 to 13), and contact 219 (6) of the appropriated finder circuit sequence switch, from which point it extends to ground at the right-hand back 95 contact and armature of the relay 61 over the path already traced. This circuit for the energization of relay 30 is open either in the cam 219 of a preceding finder sequence switch in the series, or in contacts of the 100 relay 54 or 61 as long as any sequence switch of the series is in positions 4 to 9. That is, it is open from the time the line finder switch of any associated finder circuit finds 105 a calling line until the cord finder switch of that circuit has moved far enough to trip the brushes corresponding with the selected group, as will be described. Not until this has occurred will the above-traced circuit of 110 the awaiting finder circuit be closed. When the circuit is closed, the relay 30 attracts its 115 armatures and completes a circuit that extends from battery through the motor magnet and sequence switch contact 202 (6 to 7) of the sequence switch 200, right-hand 120 front contact and armature of relay 30, sequence switch contact 208 (2 to 7), conductor 70, and segment M and corresponding brush of the cord selector commutator to ground. The completion of this circuit 125 moves finder sequence switch out of position 6.

When the sequence switch 200 reaches po-

sition 63, it closes a circuit that extends from battery by way of the winding of relay 55 (Fig. 6), conductor 71, sequence switch contact 228 (6 $\frac{1}{4}$ to 8), conductor 242, conductor 66, and segment M and corresponding brush of the line finder commutator to ground. The operation of the relay 55 applies ground to the conductors 81 extending to all of the operators' positions. At each of the positions where the operator is at her station and is in readiness to receive a call, the associated relay 91 (Fig. 7) is inert, and the operator's telephone sequence switch 300 is in its 1 position. Consequently at each of such positions, a circuit is closed that extends from battery, through the winding of the associated relay 92, armature and back contact of relay 91, sequence switch contact 304 (1), conductor 81, inner armature and front contact of relay 55 to ground. The relay 92 of each awaiting position therefore attracts its armature and closes a circuit that extends from battery, through the front contact and armature of the relay 92 to the conductor 82, and thence to ground by way of the windings of the relays 77 corresponding to operator's position at the various cord selector frames.

When the finder sequence switch 200 reaches position 7, in which position it comes to rest, it closes a circuit that extends from battery through the winding of relay 54, left-hand back contact and armature of relay 61, conductor 73, finder sequence switch contact 228 (7 to 8), conductor 242, conductor 66, and segment M and corresponding brush of the line finder commutator to ground. Relay 54 attracts its armatures and completes a branch of the circuit traced above, which branch extends from conductor 73 by way of the left-hand armature and back contact of the relay 61, armature and front contact of relay 63, front contact and inner armature of relay 54, armature and front contact of relay 77, (which relay is energized, as previously described, as a result of the corresponding operator's position being in readiness to receive a call), right-hand back contact and switch spring of relay 93 of the corresponding group, winding of associated relay 94, winding of relay 93, left-hand switch spring and resting contact of relay 93, conductor 83, left-hand back contact and armature of relay 95 at the O operator's position to battery. Upon the closure of the above-traced branch circuit, group relays 93 and 94 are energized in parallel with the relay 54. Relay 93 in operating disconnects its own energizing winding and that of relay 94 from the previously traced path to battery by way of the left-hand back contact and armature of relay 95, and connects them in a path which extends to battery by way of con-

ductor 84 and the winding of the relay 95. 65 This causes the relay 95 also to be energized and to interrupt in its left-hand armature and back contact the path by way of conductor 83 over which the relays 93 and 94 were initially energized.

Relay 94 in operating closes a circuit from battery through the winding of the trip magnet 20 corresponding to the selected operator's position, and to ground by way of the right-hand armature and front contact of the relay 94. This relay also closes a circuit that extends from battery through the winding of the relay 63 and the left-hand armature and front contact of the relay 94 to ground. The relay 63 in operating 75 closes a branch that extends from the conductor 73 (grounded at contact 228 (7 to 8) of the line finder sequence switch) through the armature and front contact of relay 63, conductor 72, sequence switch contacts 220 80 (7) and (1 to 13), and left-hand winding of relay 30 to battery. A branch energizing path for relay 30 also extends from conductor 72 by way of sequence switch contacts 220 (7), conductor 241, right-hand winding 85 of relay 30, sequence switch contacts 217 (2 to 9), and resistance 56 to battery. Relay 30 attracts its armatures and closes a circuit that extends from battery through the motor magnet and sequence switch contact 202 (6 95 to 7), front contact and right-hand armature of relay 30, sequence switch contact 208 (2 to 7), conductor 70, and segment M and corresponding brush of the cord selector commutator to ground. The closure of this circuit moves sequence switch 200 out of position 7. Furthermore, relay 30 in operating is locked up over a circuit that extends from battery through resistance 56, sequence switch contacts 217 (2 to 9), right-hand 100 winding of relay 30, sequence switch contacts 216 (7 to 9) and (2 to 9), front contact and left-hand armature of relay 30 and armature and back contact of relay 52 to ground.

When the sequence switch reaches position 8 it closes a circuit that starts the upward movement of the brush-carrying rod of the cord finder switch, this circuit extending from battery through the up-drive magnet 115 34 of the cord finder, conductor 89, sequence switch contact 207 (8 to 9), right-hand front contact and armature of relay 30, sequence switch contact 218 (8 to 9), conductor 66, and segment M and corresponding brush of 120 the line-finder commutator to ground. At the outset of the upward movement of the cord finder brush rod the tripping levers of the various sets of brushes are brought simultaneously into operative position with 125 respect to the corresponding tripping yokes, and that set of brushes is tripped and made operative whose trip magnet is at the time

energized. In the present instance, it is assumed that this is the trip magnet 20 associated with the terminals of the group of connecting cord circuits extending to the O 5 operator's position.

Immediately after the set of brushes is tripped, the common operator's selecting circuit is restored so as to be available for the use of other cord finder switches. This 10 is effected through the medium of a circuit that is completed by the grounding of the K segment of the cord finder commutator, this segment being so located as to be engaged by its brush immediately after the tripping 15 levers of the sets of brushes pass the associated tripping yokes. The circuit referred to extends from battery, through the winding of relay 61, conductor 74, sequence switch contact 221 (7 $\frac{1}{2}$ to 8), conductor 180, 20 cord finder commutator segment K and its corresponding brush to ground. Relay 61 in operating opens in its left-hand back contact the previously-traced circuit by way of conductor 73 which, up to this time, has been 25 holding energized the relay 95 at the O operator's position and the relays 93 and 94 corresponding to this position on the cord finder frame. The release of the relay 94 deenergizes the corresponding trip magnet 20 and the common relay 63. The deenergization of the relay 93 reestablishes, subject to the release of relay 61, the control of other finder circuits over the brush-tripping mechanism of the associated cord finder frame.

35 Relay 61 in operating closes a locking circuit for itself to ground by way of conductor 73 and sequence switch contact 228 (7 to 8). It also completes a circuit that extends from battery through the motor magnet and 40 contact 225 (8) of the sequence switch 200, conductor 75, right-hand front contact and armature of relay 61 to ground. The closure of this circuit moves sequence switch 200 out of position 8. In moving out of 45 position 8, the sequence switch opens its contacts 228 (7 to 8) and 221 (7 $\frac{1}{2}$ to 8), thus deenergizing relay 61 and again extending conductor 73 to the relay 54 and the conductors over which the operator's selection is 50 effected. In closing its right-hand back contact upon release, relay 61 also restores the continuity of conductor 76 and makes it available for moving out of position 6 the sequence switch of some other finder circuit 55 which may be waiting for access to the operator's selecting circuit.

When the sequence switch 200 is moved out of position 8, it moves into position 9 and there awaits the finding of an idle connecting cord circuit upon the operator's position that has been selected. As the brush-carrying rod moves up, the brushes 111, 112, 113 and 114 of the set that has been tripped come into engagement with sets of terminals 65 115, 116, 117 and 118 corresponding with

the different connecting cord circuits located at that operator's position. When a cord circuit is not in use, its corresponding terminal 118 is connected to high potential battery; and when the terminals of such a connecting circuit are encountered, a path is completed that extends from ground through the winding of relay 52, sequence switch contacts 226 (8 to 9), conductor 99, brush 114, terminal 118, conductor 88 of the cord circuit, contact 161, which is closed when the associated cord is not in use, right-hand back contact and armature of relay 119, resting contacts and winding of common relay 244 to high potential battery. Current flowing in this circuit causes the relay 52 to attract its armature and break the previously-traced circuit by way of sequence switch contacts 216 and 217 and the right-hand winding of relay 30 which, up to this time, has been holding relay 30 energized. When the relay 30 is released it opens, in its right-hand front contact, the previously-traced circuit including the up-drive magnet 34, and thus causes the brushes of the cord finder switch to come to rest on the terminals of the selected cord circuit. The relay 30 in releasing also closes a circuit that extends from battery through the motor magnet and contact 202 (8 to 9) of the sequence switch 200, 90 back contact and right-hand armature of relay 30, sequence switch contact 218 (8 to 9), conductor 66, and segment M and corresponding brush of the line finder commutator to ground. The closure of this circuit 95 moves the sequence switch 200 out of position 9, whereupon it moves, under the control of its cam 201, into position 14, which is the talking position of the finder circuit.

100 Turning now to the automatic control exercised by the operators' selecting circuits over the apparatus that governs the grouping operations, it will be remembered that the finder sequence switch 200 is moved out of position 4 when the line finder brushes 105 engage the terminals of the calling line; that the sequence switch waits in position 6, the next resting position, until the circuit of conductor 76 to ground is closed by the completion of the operator-selecting operation 110 of some other finder circuit of the group; that the finder sequence switch is moved out of the next resting position, 7, by the setting of the trip magnet 20 or 21 of the selected operator's position; and that it is moved 115 out of the next resting position, 8, by the grounding of the K segment of the cord selector commutator as the elevator in rising completes the tripping of the selected brushes. The advance of the finder sequence 120 switch 200 from position 4 to position 9 is unattended by any considerable delay if the apparatus is functioning properly. If the advance is delayed to an extent which shows 125 that the apparatus is not operating properly, 130

it is desirable, as this apparatus is common to all of the finder circuits of the particular sub-group, to divert the calls from this sub-group and route them exclusively into the 5 other sub-group.

Normally the sequence switches 200 of all of the finder circuits are in one or another of the positions 9 to 4, and a circuit is completed that extends from battery, through the winding 10 of the slow releasing relay 160, conductor 139, sequence switch contacts 219 (9 to 4) of all of the finder sequence switches in series, conductor 76, outer armature and back contact of relay 54, and right-hand 15 back contact and armature of relay 61 to ground. The relay 160 is therefore normally maintained energized. When one of the 20 finder sequence switches reaches the stage in which the operator's position is to be selected, in moving out of position 4 it opens at its sequence switch contacts 219 (9 to 4) the circuit just traced. This breaks the energizing circuit of relay 160. But if the apparatus is operating properly, before the 25 slow-acting relay 160 has time to release its armatures a circuit is completed for maintaining its energization by way of the left-hand armature and front contact of relay 168 and the outer armature and front contact of relay 55 to ground. The relay 55 has had its energizing circuit closed from the 30 time the finder sequence switch reached position 6 $\frac{1}{2}$, and the energizing circuit of the relay 168 is closed by way of conductor 73 and sequence switch contacts 228 (7 to 8) when the finder sequence switch 200 moves 35 out of its waiting position 6. If there should be any undue delay in the completion of this alternative holding circuit for the relay 160 after the sequence switch of the seeking 40 finder circuit moves out of position 4, the relay 160 would release its armature and would close a circuit from battery by way of the left-hand winding of relay 167 and the 45 back contact and switch spring of relay 160 to ground. In such case the operation of relay 167 closes a circuit that extends from battery through the winding of relay 135 (see Fig. 4), conductor 80, and the front 50 contact and armature of relay 167, to ground, thus energizing relay 135 and bringing about the operation of the associated grouping sequence switch, in the manner already described, to shut down the front 55 of the frame and direct the calls exclusively to the finder circuits of the back of the frame. Likewise, the same result would follow if relay 160 should release its armature as a result of an accidental and continuous 60 break in the continuity of its normal energizing circuit by way of conductor 139, the series of sequence switch cams 219, conductor 76, and the resting contacts or relays 54 and 61.

65 As described above, the advance without

undue delay of the finder sequence switch from position 4 to position 7 prevents the relay 160 from releasing its armature to close the energizing circuit of the relay 167. If after reaching position 7 the sequence 70 switch delays too long in positions 7 to 8, a circuit is closed that causes the operation of relay 135 and the diverting of calls from the associated sub-group. When the relay 168 operates as a result of the closure of its 75 energizing circuit in sequence switch contacts 228 (7 to 8), it closes a circuit which extends from battery through the winding of relay 169, and the right-hand front contact and armature of relay 168 to ground. 80 The relay 169 is made especially slow in attracting its armature and may, if desired, be a group of relays organized to accomplish this result in the manner disclosed in Patent 1,163,896 to Darrah, issued December 14, 85 1915. If, therefore, the relay 168 remains energized for an interval longer than that required for the relay, or collection of relays 169 to operate, a circuit is closed that extends from battery through the right-hand 90 winding of relay 167, armature and front contact of relay 169 and right-hand front contact and armature of relay 168 to ground. Relay 167 is thereupon energized and closes the circuit that extends from battery through 95 the winding of relay 135, conductor 80, and front contact and armature of relay 167 to ground. This actuates relay 135, which in turn brings about the operation of grouping sequence switch 500 to divert calls from 100 the subgroup G' of circuits served by the operator's selecting apparatus that is not operating properly.

The connecting circuit to which the finder circuit is extended when the finder sequence 105 switch reaches position 14, as hereinbefore described, is illustrated in the present instance as being a cord circuit terminating in a connecting plug 170 and including in its talking conductors 85 and 86 the windings of a repeating coil 159 with a bridged battery, and the usual signal controlling relays 171 and 187. The connecting circuit also includes a ringing key 104 by means of which current from the ringing generator 181 may be applied to the circuit of the called line, and a listening key 181 by means of which the connection of the operator's telephone set 147 with the called line may be controlled.

The extension of the finder circuit to the connecting cord brings about, in a manner which need not be described, the actuation of a signal on the associated operator's position which informs the operator that a 125 call is waiting. The operator's telephone is connected with the circuit by means of the listening key 181; and when the operator has learned the number of the line with which the calling subscriber desires connec- 130

tion, she completes the connection by inserting the calling plug 170 into the spring-jack 14 of that line. Before the plug is inserted, the usual busy test may be made over 5 the path that is shown extending from the tip of the plug by way of the armature and back contact of the relay 175 to a winding of the operator's induction coil 146. When the plug is inserted, a circuit is closed that 10 extends from battery through the winding of the relay 119, winding of the relay 175, the coöperating sleeve contacts of the calling plug 170 and spring-jack 14, and the winding of the cut-off relay 11 to ground. 15 The completion of this circuit causes all three relays to attract their armatures, the relay 119 opening the path by way of conductor 88 and common relay 244 to high potential battery, thus rendering the connecting cord circuit unselectable, relay 175 disconnecting the tip of the plug 170 from the test conductor and completing the talking circuit of the tip strand, and the cut-off relay 11 disconnecting the line relay 12 of the 20 called subscriber's line. Ringing current from the ringing generator 181 may then be applied to the called subscriber's line by moving the switch levers of the ringing key 104.

30 By means of appropriate mechanism which is disclosed in the patent to S. B. Williams, Jr., No. 1,304,641, issued May 27, 1919, Serial No. 180,634, filed July 14, 1917, and which it is unnecessary to describe as 35 it forms no part of the present invention, the extension of the finder circuit to the connecting cord circuit brings about the opening of the contacts of the switch 161 and the closing of the contacts of the switch 40 152. The switch 152 corresponds to the left-hand armature and front contact of relay 152 and the switch 161 corresponds to cam 404 of the sequence switch 400 of the above mentioned Williams patent. The 45 switch 161 in opening its contacts renders the associated cord circuit unselectable immediately and in advance of the opening of the contacts controlled by the relay 119. The closing of the contacts of switch 152 50 completes a circuit that extends from battery through the winding of relay 155, switch contacts 152, conductor 87, contact 117 and coöperating brush 113 of the cord selector, conductor 98, contacts 217 (9 $\frac{3}{4}$ to 14) and (12 to 16) of the finder sequence switch, right-hand winding of relay 30, sequence switch contact 212 (12 $\frac{3}{4}$ to 14), conductor 50, brush 42 and contact 46 of the line finder, conductor 53 and winding of 55 60 cut-off relay 11 of the calling subscriber's line to ground. The current that flows in this circuit keeps the relays 155, 30 and 11 energized during the time that the connection is established. The relay 155 closes a 65 normal break in the ring strand 86 of the

talking circuit. The relay 30, as long as it is energized, prevents the finder sequence switch 200 from moving out of its talking position 14. The cut-off relay 11 keeps the branch by way of the line relay 12 disconnected from the calling line.

At the termination of the conversation the replacing of the telephone receivers on their switchhooks at the calling and called subscribers' stations brings about the display of 75 supervisory signals (not shown) controlled by the cord circuit relays 171 and 187 in the usual way, and the operator in response to this indication withdraws the calling plug 170 from the spring-jack of the called subscriber's line. The withdrawal of the plug is accompanied by the opening of the contacts of switch 152. This opens the circuit traced in the preceding paragraph including the relays 155, 30 and 11, and these relays release 80 their armatures. When relay 30 of the finder circuit releases it closes a circuit that extends from battery through the motor magnet and contact 202 (14) of the finder sequence switch, left-hand back contact and 85 armature of relay 30, and armature and back contact of relay 52 to ground. This moves the finder sequence switch out of the talking 90 position 14.

When the finder sequence switch reaches 95 position 15 a circuit is closed for the energization of the relay 30 that includes in parallel branches both windings of that relay. One branch of this circuit extends from battery through resistance 56, sequence switch 100 contacts 217 (15 to 16) and (12 to 16), right-hand winding of relay 30, conductor 241 and sequence switch contacts 220 (15) and (11 to 16) to conductor 242; the other branch extends from battery, through the left-hand 105 winding of relay 30, conductor 243, and sequence switch contacts 220 (15) and (11 to 16) to conductor 242; thence both branches extend by way of conductor 242 and 66, and M segment and corresponding brush of the 110 line-finder commutator to ground. Relay 30 in operating closes a branch path to ground for maintaining its energization, this path extending from the right-hand winding of relay 30, by way of sequence switch contacts 115 216 (15 to 16), left-hand front contact and armature of relay 30, and armature and back contact of relay 52 to ground. Relay 30 in operating also closes a circuit that extends from battery, through motor magnet 120 and contact 202 (15) of the finder sequence switch, right-hand front contact and armature of relay 30, sequence switch contact 218 (15), conductor 66, and M segment and corresponding brush of the line-finder commutator to ground. The completion of this 125 circuit energizes the finder sequence switch 200 and causes it to move its cams to position 16.

In moving out of position 15 the sequence 130

switch opens, at its 220 cam, the branch of the energizing path that includes the left-hand winding of relay 30, and also the path to ground by way of conductor 66 and the 5 M segment of the line-finder commutator; the energization of the relay being maintained in position 16 of the sequence switch by way of the branch that includes its right-hand winding, cam 216, left-hand contacts 10 of relay 30, and resting contacts of relay 52. This circuit is held closed and relay 30 is kept energized until the cord circuit through which the call was extended has returned to its normal condition. When this 15 occurs a circuit is closed that extends from high-potential battery through the winding and contacts of common relay 244 (see Fig. 7), armature and back contact of relay 119, contacts 161 closed when the cord circuit returns to normal, conductor 88, cord selector 20 contact 118 and corresponding brush 114, conductor 99, sequence switch contact 208 (16), right-hand armature and front contact of relay 30, sequence switch contacts 215 (9 to 17) and (16), and winding of relay 52 to ground. The closure of this circuit energizes relay 52, which attracts its armature and opens the previously-traced holding circuit of the relay 30. Relay 30 in releasing 25 its armatures closes a circuit that extends from battery through the winding of down-drive magnet 62 of the line-finder switch, conductor 60, sequence switch contacts 223 (16 to 16½), left-hand back contact and 30 armature of relay 30, and armature and back contact of relay 52 to ground (the energizing circuit of relay 52 having been interrupted at the right-hand front contact and armature of relay 30 when that relay released). As a result of the closure of this 35 circuit, the brushes of the line-finder switch are returned to normal.

When the brushes reach their normal position, a circuit is closed that extends from battery, through the motor magnet and contact 224 (16) of the finder sequence switch, conductor 69, segment Y of the line finder commutator and corresponding brush to ground. This moves the finder sequence 40 switch out of position 16. In the next resting position 17 of the finder sequence switch a circuit is closed that extends from battery through the down-drive magnet 35 of the cord selector switch, conductor 90, sequence 45 switch contact 218 (17), conductor 66, and segment M of the line finder commutator and corresponding brush to ground. The closure of this circuit energizes the down-drive magnet 35 and causes the cord selector brushes to 50 return to their normal position. At the end of the downward movement of the brushes, a circuit is closed that extends from battery through the motor magnet and contact 224 (17) of the finder sequence switch, conductor 31, Y segment of the cord selector com-

mutator and corresponding brush to ground. The completion of this circuit moves the finder sequence switch 200 out of position 17, after which it returns to position 1 under the control of its cam 201.

70

In order that the features to which this invention is directed may be fully and clearly disclosed, it has been necessary to describe them in connection with other features that are the subject of co-pending applications assigned to the same assignee, such applications including the applications of S. B. Williams, Jr., Serial No. 75,328, filed January 31, 1916, Serial No. 75,329, filed January 31, 1916, and Serial No. 107,090, filed July 1, 1916, and the application of F. A. Stearn, Serial No. 107,540, filed July 5, 1916. Such other features are the subject of claims in the applications mentioned above, and are not claimed in this application.

75

80

85

What is claimed is:

1. The combination with a group of telephone lines and a group of operators' positions, of two sub-groups of circuits normally acting as a single group to extend calls from said group of lines to said group of positions, switching mechanism for controlling the access of calls to said group of circuits, and means controlled by the unavailability of either sub-group of circuits 90 for operating said switching mechanism to divert calls from that sub-group and confine them to the other sub-group.

2. The combination with a group of telephone lines, of two sub-groups of finder 100 switches normally acting as a single group for extending the connection of said lines, means for moving said switches, a starting conductor for each sub-group of switches for controlling the switch-moving means of that 105 sub-group, said group of telephone lines being normally in operative relation with the starting conductors of both of said sub-groups, and switching mechanism for disestablishing the operative relation between 110 said group of telephone lines and one or the other of said starting conductors.

3. The combination with a plurality of operators' positions, of a group of circuits for extending calls thereto, and a common 115 electromagnetic switching mechanism for dividing said group of call-extending circuits into sub-groups and confining the calls to one or the other of said sub-groups depending on the availability of the corresponding sub-group.

4. The combination with a group of telephone lines, of a group of finder switches to the terminals of which the telephone lines of said group are multiplied, said group of 125 finder switches being divided into sub-groups, a group of operators' positions, circuits associated with the finder switches of each sub-group for extending the circuits of said lines to the operators' positions of said 130

- group, both of said groups of finder switches being normally under the control of said lines, and means for depriving said lines of control over one or the other of said sub-
5 groups.
5. The combination with a group of telephone lines, of a group of operators' positions, a large group of finder switches consisting of a plurality of sub-groups, circuits
10 associated with each sub-group of finder switches for extending the connections of calling lines to the operators' positions of said group of positions, said large group of finder switches with their associated circuits
15 being normally active, a common operator's selecting circuit for the circuits of each of said sub-groups of finder switches, and means responsive to an abnormal condition of said common operator's selecting circuit
20 of each sub-group for making inactive the corresponding sub-group of finder switches and associated circuits.
6. The combination with a group of lines and a plurality of operators' positions, of a group of circuits normally operative to extend calls from said lines to said operators' positions, said group of circuits consisting of a plurality of sub-groups, an operator's selecting circuit for each of said sub-groups
25 of circuits, each operator's selecting circuit being responsive to the condition of said operators' positions and controlling the operation of the associated call-extending circuits, and means responsive to an abnormal
30 condition of each operator's selecting circuit for causing calls from said lines to be excluded from the associated sub-group of call-extending circuits.
7. The combination with a group of lines and a group of operators' positions, of a group of circuits for extending calls from said lines to said operators' positions, said group of circuits consisting of a plurality of sub-groups, a controlling circuit common
35 to the call-extending circuits of each of said sub-groups, and means responsive to an abnormal condition of either of said common controlling circuits for excluding calls from the corresponding sub-group.
8. The combination with a group of operators' positions, of a group of circuits for extending calls thereto, electromagnetic switching mechanism controlling said group of circuits, and means for actuating said electromagnetic switching mechanism to divide said group into sub-groups and exclude calls from the circuits of one or the other of said sub-groups when the corresponding circuits become unavailable.
50
9. The combination with a group of telephone lines, of a group of finder switches for making connection therewith, means for moving said finder switches, starting means under the control of any of said telephone lines in calling for energizing said moving
55
- means to start a finder switch, electromagnetic switching mechanism for electrically dividing said group of finder switches into sub-groups, and means made operative while said starting means is actuated for preventing said electromagnetic switching mechanism from acting to divide said group of finder switches.
70
10. The combination with a group of telephone lines, of a group of finder switches for making connection therewith, means for moving said finder switches, starting means under the control of any of said telephone lines in calling for energizing said moving means to start a finder switch, electromagnetic switching mechanism for electrically dividing said group of finder switches into sub-groups, and means made operative while said starting means is actuated for preventing said electromagnetic switching mechanism from operating.
75
11. The combination with a group of telephone lines, of a group of circuits for making connection therewith, switching mechanism for dividing said group of circuits into sub-groups and rendering one of said sub-groups unavailable for use, an electromagnetic switch responsive to the initiation of a call by any of said lines for rendering operative one of said line connecting circuits, and means controlled by said electromagnetic switch in its operation for preventing the operation of said switching mechanism.
80
12. The combination with a group of telephone lines, of a group of finder switches for making connection therewith, means for moving said finder switches, starting means under the control of any of said telephone lines in calling for energizing said moving means to start a finder switch, a grouping switch for electrically dividing said group of finder switches into sub-groups, and means made operative while said grouping switch is operating for rendering ineffective said starting means.
85
13. The combination with a group of telephone lines, of a plurality of circuits for making connection therewith, switching mechanism for electrically combining said circuits in a single large group or dividing them into a plurality of sub-groups, an electromagnetic switch responsive to the initiation of a call by any of said lines, means controlled by the said electromagnetic switch for causing one of said circuits to connect with the calling line, and means made active while said switching mechanism is operating for depriving said lines of control over said line-connecting circuits.
90
14. The combination with a group of telephone lines, of a plurality of circuits for making connection therewith, switching mechanism for electrically combining said circuits in a single large group or dividing them into a plurality of sub-groups, an elec-
125
- 65

- tromagnetic switch responsive to the initiation of a call by any of said lines, means controlled by said electromagnetic switch for causing one of said circuits to connect 5 with the calling line, and means made active while said switching mechanism is operating to combine said circuits in a single large group for depriving said lines of control over said line-connecting circuits.
- 10 15. The combination with a group of telephone lines, of a plurality of finder switches for making connection therewith, switching mechanism for electrically combining said finder switches in a single large group or 15 dividing them into a plurality of sub-groups, an electromagnetic switch responsive to the initiation of a call by any of said telephone lines, and means controlled by said switching mechanism in dividing said 20 finder switches into sub-groups for rendering one of said sub-groups inoperative and placing one of the finder switches in another sub-group under the control of said electromagnetic switch.
- 25 16. The combination with a group of lines, of two sub-groups of circuits adapted to make connection therewith, switching mechanism for bringing one or the other or both of said sub-groups into operative 30 relation with said group of lines, means actuated when either sub-group is brought into operative relation with said lines for placing a single circuit of that sub-group in condition to respond to a call initiated 35 by any line of said group, and means actuated when the other sub-group is also brought into operative relation with said lines for making unresponsive any circuit of that sub-group which may at the time 40 be in responsive condition.
17. The combination with a group of lines, of two sub-groups of circuits adapted to serve the same, switching mechanism for bringing both of said sub-groups into operative 45 relation with said group of lines or excluding either one of them, means actuated when either sub-group is excluded for placing a single circuit of the other sub-group in condition to respond to a calling 50 line, and means made operative in again including the excluded sub-group for making unresponsive any responsive circuit of that sub-group.
- 55 18. The combination with a group of telephone lines, of two sub-groups of call-ex-
- tending circuits for serving the same, switching mechanism for bringing both of said sub-groups into operative relation with said group of lines or excluding either one of them, means actuated in excluding either 60 sub-group for placing a single circuit of the other sub-group in condition to respond to a calling line, means under the control of said switching mechanism for making unresponsive any responsive circuit of said excluded sub-group, and means made operative when all the circuits of the excluded sub-group become unresponsive for moving said switching mechanism to include the said excluded sub-group in operative relation with 70 said group of lines.
19. The combination with a group of telephone lines, of a sub-group of call-extending circuits normally in operative relation therewith, means for maintaining one or 75 another of the circuits of said sub-group in condition to respond to the initiation of a call by any of the lines of said group, another like sub-group of call-extending circuits also adapted to serve said group of 80 lines, a switch for bringing said other sub-group of call-extending circuits into operative relation with said group of lines, and means for preventing the operation of said switch while any of the circuits of said 85 other sub-group is in responsive condition.
20. The combination with a group of telephone lines, of a sub-group of call-extending circuits in operative relation with said group of lines, means for maintaining one 90 or another of the circuits of said sub-group in condition to respond to the initiation of a call by any line of said group of lines, another like sub-group of call-extending circuits also adapted to serve said group of 95 lines, a switch for controlling the operative relation of said other sub-group with said group of lines, means made active in the operation of said switch for rendering unresponsive any responsive circuit of said 100 other sub-group, and means, made active when all the circuits of said other sub-group become unresponsive, for operating said switch to bring said other sub-group into operative relation with said group of lines. 105

In witness whereof, we hereunto subscribe our names this 20th day of July A. D., 1917.

SAMUEL B. WILLIAMS, JR.
RALPH L. QUASS.
